ADJUSTABLE MOTOR SUPPORTING MEANS
FOR AGRICULTURAL ELEVATORSWilhelm Vutz, Coldwater, Ohio, assignor to Avco
Manufacturing Corporation, Cincinnati, Ohio, a
corporation of Delaware

Application December 8, 1949, Serial No. 131,728

4 Claims. (Cl. 198—203)

1

The present invention relates to an adjustable supporting leg for bracing a motor mount secured to one side of a portable agricultural elevator. The invention has particular reference to an adjustable leg construction for use with an elevator incorporating a conveyor chute which may be adjusted to various elevations for efficient operation under all conditions.

The novel structure disclosed herein has particular utility when used in conjunction with an installation wherein the motor mount is secured directly to the lateral face of the conveyor chute. In such installations, a particular advantage of the invention is its provision of excellent support for the motor mount, regardless of the required inclination of the elevator conveyor chute during periods of operation.

An object of the present invention is the provision of an adjustable motor mount supporting leg structure that can be easily and quickly swung into a convenient unobstructing position parallel to the axis of the conveyor chute when operation of the elevator is discontinued and the chute is to be lowered into its inoperative, transportable position.

It will be obvious from this disclosure that another object of the invention is the provision of a cheap and simple supporting structure that can be adjusted to support the motor mount of an elevator during all periods of its operation without interference with the tension or adjustment of any drive belts operatively connected to a motor or engine supported by the mount.

The novel structure disclosed has the additional advantage of preventing the imposition of a transverse torque on the conveyor chute, thereby precluding the formation of abnormal stresses and strains detrimental to the elevator structure.

A particular advantage of the present invention is that it provides uniform support for the elevator motor mount during periods of operation thus preventing twisting of the motor mount and possible resultant misalignment of the motor or other power supply means supported thereby.

The novel features that are characteristic of the invention are set forth in the appended claims; the invention itself, however, both as to its organization and method of operation, together with additional objects and advantages thereof, will best be understood from the following description of a specific embodiment when read in conjunction with the accompanying drawings, in which:

Figure 1 is a front elevational view of the lower

2

end of an elevator conveyor chute showing an internal combustion engine operatively associated therewith and fully supported by the novel adjustable supporting leg structure disclosed herein.

Figure 2 is a side elevational view showing the lateral relationship of the conveyor chute, engine, and leg structure.

With reference to the figures, it will be noted that a structure made according to the teaching of the present invention may be used to advantage with an agricultural elevator comprising a conveyor chute 1, having secured to its lower end a hopper 2. The conveyor chute is pivotally attached to a reach tube 3 which may be releasably secured to a portable truck (not shown) and may be inclined at various angles relative to the ground level to facilitate the transfer of farm produce, supplied to a hopper 2, from the ground level to a storage bin at a higher elevation.

The power for driving the elevator and conveying the farm produce is supplied by power supply means, such as an internal combustion engine 4, which may be supported by a motor mount generally designated 5, rigidly secured to lateral face 6 of the conveyor chute. A conventional gear reduction unit 7, driven by a belt 8, is operatively connected with the conveyor chute. The belt is driven by pulley 9 of engine 4 and is in driving engagement with pulley 10 of the gear unit.

The motor mount, constructed according to the present invention, incorporates a crossbar 11 which is rigidly secured to the lower face of the conveyor chute and extends laterally and outwardly therefrom as best shown in Figure 2. Longitudinal supporting members 12, disposed parallel to lateral face 6 of the conveyor chute, are secured at one end to crossbar 11 and at the other end to another laterally extending bar 11a rigidly fastened to and projecting from lateral face 6.

A mounting plate 13 to which engine 4 is secured is supported by members 12 and is provided with conventional adjusting slots and bolts 14. A take-up bolt 15 is also provided between an upstanding ear 11a, secured to crossbar 11, and the mounting plate proper for facilitating tension adjustment of belt 8 in a standard manner as required.

It will be obvious to those skilled in the art that, without some means for carrying part of the weight of the engine and its mounting plate, a considerable transverse torque will be imposed on the conveyor chute, creating abnormal stresses and strains therein. These stresses, in conjunc-

tion with the normal vibration of the engine and conveyor chute incidental to ordinary operation, foster fatigue failures at various points in the structure. This unfavorable condition can be avoided by the provision of an adjustable supporting leg 16 pivotally secured at 17 to an outstanding end of crossbar 11. The lower end of the leg is provided with a ground shoe 18 for distributing the load carried by the leg over a relatively large ground area. A slotted cross-brace 19, pivotally secured near the midpoint of leg 16, as at 20, is engaged by a clamping handle 21 threadedly secured to an outstanding end of the other crossbar.

As the elevator is adjusted to any desired operating position, shoe 18 may be swung into engagement with the ground merely by loosening clamping handle 21, thereby permitting the slotted cross-brace 19 to slide to a position commensurate with that of leg 16 when the ground shoe is properly positioned. Handle 21 is tightened thereafter, thus rigidly clamping the structure and assuring full and uniform support for the outer corners of the motor mount. The supporting leg and brace thus not only prevent twisting of the conveyor chute but also prevent twisting of the motor mount and any resultant misalignment of the driving engine.

Ordinarily, the conveyor chute is lowered to a more or less horizontal position to facilitate transportation of the elevator to a new location of activity, and for this reason, it will be apparent that an advantage of the herein disclosed structure is that it can be easily and quickly swung to a position more or less parallel to the axis of the conveyor chute, in which position it does not hinder in any way the transportability of the elevator.

Persons experienced in the use and manufacture of farm implements will readily recognize that the novel structure taught by the present invention is not only simple and convenient to use but may be cheaply and easily fabricated from low cost materials.

The preferred embodiment of the invention has been described with reference to an internal combustion engine as the driving means. Other types of motive power, such as electric motors, may be used without modifying the utility or applicability of the present invention in any way.

Having described a preferred embodiment of my invention, I claim:

1. In combination with an agricultural elevator having a conveyor chute, a motor mount rigidly secured to the conveyor chute and extending laterally outwardly therefrom, a rigid supporting leg pivotally secured to an outstanding portion of said motor mount for ground engagement and an adjustable brace pivotally secured to said supporting leg near its midpoint and releasably secured to another outstanding portion of said motor mount.
2. In an agricultural elevator having a conveyor chute, motor supporting means rigidly secured to and laterally extending from the conveyor chute, motor mounting means adjustably secured to said laterally extending means, a ground supporting leg pivotally secured to an extending portion of said laterally extending means, an adjustable brace pivotally secured to said supporting leg at a point remote from its pivotal attachment to said laterally extending means, and means for releasably securing said brace to a portion of said laterally extending means spaced from the point of pivotal attachment of said supporting leg.
3. Apparatus as defined in claim 2 and, in addition, a ground shoe secured to the end of said supporting leg remote from its pivotal attachment to said laterally extending means.
4. In combination with an agricultural elevator having a conveyor chute, a motor mount secured to the conveyor chute and extending outwardly therefrom, a rigid supporting leg pivotally secured to a portion of said motor mount for ground engagement and an adjustable brace pivotally secured to said supporting leg and releasably secured to another portion of said motor mount.

WILHELM VUTZ.
